UNITED STATES PATENT OFFICE.

JOHN L. DAWES, OF PITTSBURGH, PENNSYLVANIA.

DESIGN FOR A LAMP-CASING.

50,094.

Specification for Design.

Patented Dec. 26, 1916.

Application filed October 9, 1916. Serial No. 124,731. Term of patent 7 years.

To all whom it may concern:

Be it known that I, JOHN L. DAWES, a citizen of the United States, residing at Pittsburgh, Allegheny county, Pennsylvania, have invented a new, original, and ornamental Design for Lamp-Casings, of which the following is a specification, reference being had to the accompanying drawing, forming part thereof, in which:

2 is a plan view partially in section of my new design.

I claim:

The ornamental design for a lamp casing, as shown.

In testimony whereof, I have hereunto set my hand.

JOHN L. DAWES.

Witnesses:

JESSE B. HELLER,
H. M. CORWIN.
